FILL WIRE INSERTING MEANS

George E. Meckley, Abbottstown, Pa., assignor to Hanover Tool Company, Inc., Hanover, Pa., a corporation of Pennsylvania

Filed June 26, 1962, Ser. No. 205,329
3 Claims. (Cl. 139—127)

This invention relates to wire feeding mechanisms and, more particularly, to an intermittent drive for feeding predetermined lengths of weft or fill wire across a loom for weaving wire screen.

In wire screen looms of the type for which the subject fill wire feeder is adapted, a shed, formed by the warp wires, is successively opened in one direction, closed, and opened in the opposite direction by the heddles. In contrast to the type of loom wherein the weft is formed by a continuous fill wire woven back and forth through the successively opened sheds by a shuttle, the fill wire, which is drawn from a supply reel, is passed through the shed each time it opens and is then cut so that its respective ends project slightly beyond the outside warp wires. The projecting ends of the fill wires are then turned back and interwoven between the outer two warp wires by a tucker. The warp take-up then advances and a succeeding length of fill wire is again fed through the next succeeding shed. In order to guide the fill wire as it passes through the open shed, comb-like guide fingers are projected upwardly so as to interdigitate between alternate pairs of the warp wires which, at that time, constitute the lower portion of the shed. Looms of this general type have been used for many years for weaving fence wire and screens of large mesh. However, in the prior art looms, high speed and extreme accuracy in timing were not of the essence, nor was provision made for quick change in the width of the weave. The loom for which the subject fill wire feeder is intended is designed for about three hundred picks per minute. Keeping in mind that the fill wire feeder must shoot out as much as a thirty-six inch length of fill wire five times per second, and taking into account that the terminal portions of each one-fifth second interval are not available for projection of the fill wire, the allocatable interval during which the fill wire-driving mechanism must start, do its work, and then come to a complete stop is of extremely short duration. To meet these requirements alone, it is apparent that the fill wire drive must be substantially devoid of backlash, and the masses of the parts which do the starting and stopping must be held to the minimum to reduce inertia and momentum. One of the objects of the invention is to meet the foregoing requirements.

A further object is to provide a fill wire feeder wherein the length of the wire, which is intermittently fed thereby, can be easily adjusted to extremely accurate dimensions. In prior art wire screen looms, many time consuming changes in both the warp and the weft handling mechanism were required so that, as a practical matter, weave-width changes were seldom made. However, in the loom for which the present feeder is designed, certain improvements in which are disclosed in my co-pending application, entitled Wire Guide and Tuckers for Wire Cloth Looms, Serial No. 247,047, filed December 26, 1962, the width of the weave is quickly adjustable, with but minor changes, to meet customer demands for short runs of various widths, such as 29½" or 22¼", instead of a standard 36" width. Consequently, in the drive-length determining mechanism, wherein change-speed gears similar to those on a lathe could previously be used for varying, in fairly closely spaced steps, the length of the fill wire to be fed for each pick, it is now intended to provide a continuously variable mechanism so that the length of fill wire feed, as measured in degrees of drive

wheel turning, can be selectively and quickly predetermined to any desired length with nearly zero tolerances.

These and other objects will be apparent from the following specification and drawings, in which:

FIG. 1 is a plan view of the fill wire feed mechanism, showing the adjacent portion of the loom with the lower portion of the casing enclosing the drive mechanism removed, the removed parts being shown in FIG. 5;

FIG. 2 is an elevation of the rear side of the feed mechanism, showing the back-up idler in cross-section;

FIG. 3 is a vertical cross-section approximately along the line 3—3 of FIG. 5, with the drive wheel not shown, and with the lever 56 midway of its working stroke;

FIG. 4 is a vertical fragmentary cross-section showing the drive wheel and magnetic brake;

FIG. 5 is a plan view showing the feed mechanism with the cover-plate removed, showing lever 56 at the end of a working stroke; and,

FIG. 6 is an end elevation of the feed and cut-off mechanism as seen from the inboard side.

Referring first to FIGS. 1 and 2 of the drawings, in which like reference numerals denote similar elements, the fill wire feeder 2 is mounted on the frame 4 of a wire screen loom 6. In order to place the invention in its environment, it will be understood that warp wires are supplied by creels and pass over various tensioning rolls, a whip roll and guides, none shown, to heddles 8 and 10. One set of warp wires is lifted by one heddle while the alternate set is lowered, and then vice-versa, thereby opening, closing and reopening the shed. All the warp wires pass through a reed 12 on a laybar. As the shed opens, guide fingers 14 project upwardly past the lower wires of the shed, it being sufficient here to observe that each finger is in two parts having opposed half-eyelets. When the fingers are together, they form a closed eyelet which constitutes a guide for the fill wire which traverses the warp, and then the fingers open to free the cross-woven fill wire from the guide eyelets.

The fill wire 16 is drawn through a tube 18 from a conventional supply reel, not shown, by means of a drive wheel 20. Tube 18 is an infeed guide means through which fill wire 16 is fed tangentially against drive wheel 20. A back-up idler 22 is mounted on the end of a lever 24 pivoted at 25 and biased by a compression spring 26 so that idler 22, unless held disengaged by a toggle lever 27 detailed below, holds the fill wire tightly against the periphery of drive wheel 20.

Beyond drive wheel 20, the fill wire passes through a split tube 28 consisting of upper and lower parts 28a and 28b, past a knife 30 and thence through the open shed, being guided by the series of eyelets formed by guide fingers 14. Split tube 28 is an outfeed guide means for the fill wire. When a predetermined length of wire has been fed by drive wheel 20 through the open shed, the two portions of each of the fingers 14 separate to free the wire, the fingers retract diagonally downwardly as the shed closes around the fill wire, knife 30 severs the fill wire, the guide fingers 14 retract as the laybar advances to beat the fill wire in and the warp take-up operates to advance the weave one step. Meanwhile, as one fill wire is fed across the warp, tuckers 32, one on each side of the loom, bend and weave into the then open shed the projecting ends of the previously fed fill wire. It is the feeding and cutting mechanisms 2 and 30 with which this application is directly concerned.

Referring particularly to the more detailed FIGS. 3, 4 and 5, the drive mechanism for the fill wire feeder is enclosed in a casing 34 shown with the top 36 removed in FIG. 5. A power input drive shaft 38, which is driven by and rotates in synchronism with the main drive shaft for the other loom parts, is horizontally supported in the lower portion of casing 34 by bearings 40 and 42. A bevel

gear 44 keyed on drive shaft 38 meshes with and drives a bevel gear 46 affixed on the lower end of a vertical shaft 48, the latter being supported in bearings 50, 52. Affixed on the top end of vertical shaft 48 is a head plate 54 which, as will soon be apparent, forms a part of the variable output drive.

A lever 56 of the third class having one end pivoted at 58 in casing 34 extends across and above head plate 54, and on the under side of the lever is a slideway 60. A block 62 slidably engaging in slideway 60 is rotatably supported on a bearing post 64 projecting upwardly from a slide 66 engaged in groove 68 which extends diametrically across head plate 54. The radial distance of slide 66 from the axis of rotation of head plate 54 is adjusted by a lead screw 70, the head end of which is rotatably captive in the head plate as denoted at 72, and the threads 74 of which engage in a threaded bore through slide 66 as denoted at 76. If lead screw 70 is adjusted so that the axis of bearing 64 is coaxial with the axis of shaft 48, block 62 has zero angular velocity and hence lever 56 does not swing when shaft 48 rotates. Maximum swing of lever 56 is obtained by adjusting lead screw 70 so that slide 66 is in its outermost radial position as illustrated in FIG. 3 and, of course, the various intermediate positions of slide 66 result in corresponding angular movements of lever 56. Cross head drives of the type thus far described have been used for oscillating motions of variable stroke length, for example, in the Hazelton Patent No. 1,599,174.

On the free end of lever 56 is a segment gear 78 which engages a pinion 80 affixed, as at 82 to the base 83, i.e., the driving member, of a one-way clutch 84, one usable example of which is a Formssprag model HPI-440. The driven member of clutch 84 is a vertical shaft 86 rotatably supported in casing 34 by bearings 88, 90. A magnetic brake 92 affixed on the casing engages the upper end of shaft 86 when energized by a conventional circuit 87 including a switch 89, which is closed by a cam 91 on shaft 88 for about 270° of rotation of head plate 54. Starting from the condition shown in FIG. 3, wherein lever 56 has completed about one half of its driving stroke, one-way clutch 84 is then turned in its driving direction, and when brake 92 becomes energized, it exerts a drag on the drive train during the latter half of the driving stroke of lever 56. Thus, any tendency of the drive train to over-run, following completion of the driving stroke of lever 56 is overcome; when the drive stroke is completed, brake 92, being already energized, locks the drive train or drive wheel 20, and keeps it locked during the return stroke of lever 56. After head plate 54 rotates counter-clockwise 180° during its return stroke from the position as seen in FIG. 5, the energizing circuit 87 opens and the brake releases shaft 86 for the first half of the ensuing drive stroke of lever 56 in which drive through clutch 84 is established. An output drive gear 94 affixed on shaft 86 drives a pinion 96 (FIG. 4) on a vertical shaft 98 supported in bearings 100, 102. Fill wire drive wheel 20, being affixed on the upper end of shaft 98 is hereby unidirectionally rotated through one-way clutch 84 a predetermined number of degrees, depending upon the radial setting of slide 66, with each working stroke of lever 56. Upon completion of the working stroke of lever 56, magnetic brake 92, which therefore exerted a drag instantaneously seizes shaft 86 thereby locking through gear 94 and pinion 96 shaft 98 and drive wheel 20 until the next working stroke of lever 56. The number of degrees of rotation of drive wheel 20 determines the length of fill wire which is fed through split tube 28. One desirable characteristic of this drive mechanism, in addition to its zero backlash characteristics, is that the instants of starting and stopping of the fill wire remain the same with respect to the operating cycle of the machine, regardless of the selected length of wire fed during each cycle, thus making it unnecessary to time the mechanism each time a feed-length adjustment is made. Also, the magnetic brake, which exerts a drag on the drive

train during the latter portion of the working stroke of lever 56 and positively locks the fill wire drive wheel upon completion of the working stroke of lever 56 avoids any tendency of the mechanism to over-run, chatter or play as the slide rotates through the dead center FIG. 5 position and the one 180° therefrom, and it also prevents any frictional drag-back through clutch 84 when lever 56 starts on its return non-working stroke.

Back-up idler 22 (FIGS. 1, 2 and 5) is rotatably supported by a bearing 104 on the lower end of a stub post 106 which is supported on the end of a mounting 108 on the free end of lever 24, the latter being pivoted at 25 intermediate its ends. The compression of spring 26 is adjusted by a screw plug 112 in the end of fixed arm 114, so that when the toggle of lever 27 is broken, as in FIGS. 1 and 5, spring 26 forces back-up idler 22 against drive wheel 20 so as to compress fill wire 16 tightly therebetween, it being apparent that the return of toggle lever 27 will swing lever 24 clockwise, as seen in FIGS. 1 and 5, so as to hold idler 22 away from the fill wire and drive wheel. Tube 28 is cut away on opposite sides to accommodate the peripheries of drive wheel 20 and idler 22.

The inboard portion of tube 28 is longitudinally split, and the top half is supported by arms 116, 118 pivoted in bearings 120, 122 on an inboard extension 124 of casing 34, the lower half being stationary. A toggle lever 126 is connected to arm 118 so that the upper half of the split tube can be clamped shut or open, the latter being for clean-out in case of jam-up of the fill wire.

Referring particularly to FIGS. 1, 5 and 6, knife 30 is on the free end of a lever 128 pivotally supported by a shaft 130° in bearing 130 on a bracket 132 on the inboard end of casing extension 124. Pivoted at 134 to the other end of lever 128 is a link 136 whose lower end is pivoted at 138 to one end of a lever 140. Lever 140 is affixed on a rotatably supported shaft 142. A tension spring 144 anchored at 145 on bracket 132 is connected at 146 to the free end 148 of lever 140 so that, through this link and lever system, knife 30 is normally biased by spring 144 clockwise upwardly to the FIG. 6 position. Also affixed on lever shaft 142 is a cam 149 and on the lay bar assembly (not detailed) is a rod 150. As the lay bar completes its lay stroke, rod 150 engages cam 149 and swings further to the left from the FIG. 6 position, thereby swinging knife 30 down so as to chop off the fed fill wire and, as the lay bar returns to its dotted line position, spring 144 swings lever 140 clockwise until it engages stop screw 152 so that knife 30 is raised away from the feed path of fill wire 16.

The invention is not limited to the details shown and described, but is intended to cover all substitutions, modifications and equivalents within the scope of the following claims:

I claim:

1. In a strand feeding device including a support, a feed wheel having an annular strand-driving surface, means rotatably mounting said feed wheel on said support, infeed guide means on said support for guiding a strand from a source of supply substantially tangentially of and towards said surface, outfeed guide means on said support for guiding said strand substantially tangentially of and away from said surface, back-up means on said support for pressing said strand against said surface, and drive means for said feed wheel comprising: a lever, means mounting said lever on said support for oscillation about a first axis, a rotating driving member, means mounting said driving member on said support for rotation about a second axis, said driving member having a crank pin engaging said lever for oscillating said lever about said first axis, means for adjusting the radial position of said crank pin with respect to the second axis, whereby the length of stroke of the lever for each rotation of the driving member may be adjusted, a quadrant gear on said lever, a pinion rotatably mounted on said support and meshing with said quadrant gear whereby said pinion rotates in one

direction by a forward stroke of the lever and in an opposite direction by a return stroke of the lever, a drive train including a one-way clutch having an input member connected to the pinion and an output member connected to the feed wheel for driving the feed wheel with the forward stroke of the lever, a brake connected between the support and the drive train between the clutch and the feed wheel, and means actuated by the drive member for setting the brake during a final portion of the drive stroke and the return stroke of the lever.

2. The combination claimed in claim 1, said brake including an electro-magnetic setting mechanism, the means actuated by said drive member including an energizing circuit for said electromagnetic setting mechanism, a switch in said energizing circuit, and cam means rotating with said driving member engaging said switch for closing the same during substantially 270° of rotation of said driving member and for opening the same during substantially the next 90° of rotation of the driving member.

3. In a strand feeding device including a rotatable feed wheel having an annular strand driving surface, a one-way intermittent drive mechanism for said feed wheel, comprising: a pinion, an oscillating lever having a gear on a free end thereof meshing with said pinion for alternately rotating the latter in first and second opposite directions respectively upon feed and return stroke oscillatory movement of said lever, a drive train connecting said

pinion and said drive wheel, said drive train including a one-way clutch engaging upon rotation of the pinion in said first direction whereby to rotate said drive train a number of degrees in one direction, said clutch disengaging upon rotation of the pinion in said second direction, drive means including a stroke-length adjusting mechanism for oscillating said lever, whereby the number of degrees of rotation of said drive wheel may be varied, a magnetic brake engageable with said drive train for preventing rotation thereof opposite to said one direction, electric circuit means for energizing said magnetic brake, said circuit means including a switch for opening and closing the same, and means moving with said lever for closing said switch throughout a latter portion of the feed stroke movement of said lever and during the return stroke movement of the lever, the last-named means operating to open the switch throughout an initial portion of the feed stroke movement of the lever.
